UNITED STATES PATENT OFFICE.

FREDERICH W. KUEFFER, OF TULSA, OKLAHOMA, ASSIGNOR TO GEORGE F. EASTIN, E. A. LEWIS, F. W. KUEFFER, AND JACOB COLE, TRUSTEES OF THE SAFETY OIL TANK COMPANY, OF TULSA, OKLAHOMA.

OIL TANK.

Application filed April 23, 1921. Serial No. 464,021.

To all whom it may concern:

Be it known that I, FREDERICH W. KUEFFER, a citizen of the United States, residing at Tulsa, in the county of Tulsa and State 5 of Oklahoma, have invented new and useful Improvements in Oil Tanks, of which the following is a specification.

This invention relates to oil tanks and more particularly to those oil tanks which 10 are constructed with a floating roof instead of a stationary roof.

The principal objects of the invention are to provide a floating roof which will reduce evaporation to a negligible quantity, eliminate all gas pockets and provide a means whereby the oil will be permitted to overflow without damage to the floating roof in case the tank is inadvertently or accidentally oversupplied.

20 Other objects of the invention consisting of novel features of construction and arrangements of parts will become apparent on reference to the following specification which describes the invention in connection 25 with the accompanying drawings.

In the drawings:

Fig. 1 is a central vertical section through the tank.

30 Fig. 2 is an enlarged vertical section through a portion of the float.

Fig. 3 is an enlarged plan view of the float with certain parts broken away.

The numeral 10 designates the base of the tank, 11 the upright side wall or shell thereof, 35 of which is usually cylindrical in form and composed of a large number of plates suitably riveted together. Columns 12 extend at intervals vertically upward and are secured to the shell 11 of the tank for bracing the same and also project upwardly above 40 the tank. A plurality of intermediate posts 13 and a center post 14 also extend upwardly from the base and terminate above the tank in flanges or plates 15 and 16 which are level 45 with the top of the columns 12. Beams 17 extend radially from the plate 16 and rest on the aligning flanges 15 and the tops of corresponding columns 12. These beams are secured to the columns and posts by any suitable fastening devices such as rivets or bolts.

50 A float or open casing 18 is provided with a body having a base 19 formed with suitable apertures through which posts 13 and

14 extend, and cylindrical side wall 20 composed of structural plates suitably secured 55 together in fluid tight relation. An angularly disposed or slanting section 21, extending annularly around the body connects the base 19 to the side wall 20. The diameter of the side wall 20 is slightly less than the 60 diameter of the shell 11 of the tank and the float is so positioned as to leave an annular space 22 between the float and the tank. My invention is chiefly concerned with the means 65 employed for sealing this space against evaporation, which means will automatically yield for passing obstructions such as rivet heads, without binding the float.

According to my invention, for this purpose, use is made of a plurality of wooden 70 blocks 23 having tapered surfaces 24 which are adapted to abut against the slanting section 21. These wooden blocks 23 are arranged completely around the float and in order to seal the openings between adjacent 75 blocks, each block is provided with a metallic plate 25, such as steel or iron, having a flat portion secured to the flat upper surface of the block and bent at 26 so as to provide a slanting part corresponding to the 80 taper of the surface 24 of the block and the slope of section 21. These plates 25 are made wider than the wooden blocks so as to overlap the adjacent block at each side as shown at 27, 27', 28 and 29'. The plates 25 85 are provided with extensions of the same widths as the outer ends of the wooden blocks and these extensions are bent upwardly at 30 to form a substantially vertical surface 31 and an inwardly bent or cam 90 shaped end 32. The vertical surface 31 is adapted to contact and slide upon the interior of the shell 11, and in order to maintain this surface in firm but yielding contact with the shell a coil spring 33 is interposed 95 between the body of the float and the shell of the tank. The casing 20 of the float and the plates 31 are preferably provided with opposite bosses or lugs 34, 35 which are adapted to engage within the terminal coils 100 of the spring and thus aid in maintaining the spring and the floating blocks 23 in operating position.

In order to further seal the cracks or openings 36 between adjacent blocks, a plate 105 or strip 37 is attached to the bottom of each

block near one side thereof by means of suitable bolts or screws 38 and this strip 37 is of such width as to overlap the adjacent block and thereby cover the crack or gap 36. 5 These strips 37 need not extend the full length of the block and are therefore terminated at points slightly inward from the side wall 20 of the float. In case the oil level should approach the top of the tank it is obvious 10 that the springs 33 might expand and force the blocks 23 out of the tank. To overcome this difficulty and permit the oil to overflow from the tank without raising the float above a certain point, I provide a cam 15 39 at the top of the tank which is secured to the shell 11 and also to the columns 12. This cam extends completely around the tank and is adapted to cooperate with the cam ends 32 of the plates 25 secured to the 20 wooden blocks, so that when the float approaches the top of the tank the cam 39 will engage the cam ends 32, and gradually force the wooden blocks 23 inward against the tension of the springs 33, thus leaving a gap 25 between the float and the tank through which the oil may flow.

The float is designed so that the oil level will be substantially as indicated by the line 40. The buoyant effect of the oil will be 30 sufficient to hold the wooden blocks with the slanting surfaces of the plates 25 firmly against the angular section 21 of the float. There is no fixed connection between the float and wooden block assemblies and the 35 latter are therefore free to reciprocate relatively to the float. The overlapping top plates 25 and the bottom plates 37 which extend over the cracks between the wooden blocks, act to seal the tank against evaporation but this seal becomes more effective with continued use of the float when the slight initial evaporation from the surface of the oil results in a gummy substance accumulating in the small open places which 40 may exist between the overlapping plates, thus providing practically a complete closure for the tank.

As the float rises and falls in response to the variations in the oil level, rivet heads in 50 the shell 11 encountering cam shaped ends 32 at the top, or the corresponding cam surfaces 32' at the outer ends of the wood blocks act to force the various blocks inward separately and independently, and as soon as 55 these obstructions are passed the springs 33 force the blocks back to their original positions against the shell 11 of the tank. The small openings thus occasionally afforded by the passage of the plates 25 over the rivet 60 heads are practically the only openings through which the evaporation may take place, and in large tanks this exposure is almost negligible. The beams 17 constitute an open frame work at the top of the tank 65 and there is therefore no fixed closure under

which explosive gases may accumulate, any evaporation which may take place escapes directly into the atmosphere and the danger of the accumulation of such gases in the tank and their subsequent ignition is thereby avoided. Sleeves 41 and 42 are secured to the base 19 of the float and surround the posts 13 and 14 respectively in spaced relation, thereby providing annular spaces in which the oil may rise to the same level as in the tank without escaping into the float. 70

It will be understood that other substances than wood may be used as the material for the blocks 23 the only requirement being that those blocks and their accessory parts may be supported by the buoyant effort of the liquid. Any suitable means may be employed for filling and draining the tank but no such structure is shown as the present invention does not involve this feature, however, the type of filling and draining means shown and described in my copending application Serial No. 464,020, filed April 23, 1919, is preferred. Other changes, modifications and departures may also be made 85 from the particular construction described and shown, as this particular embodiment has been chosen for illustrative purpose merely, and the invention as defined by the claims hereunto appended may be otherwise 90 embodied and applied without departing from the spirit and scope thereof. 95

Having described my invention, what I claim as new and desire to secure by Letters Patent, is:—

1. In an oil tank, a floating roof comprising a body of smaller dimension than the shell of the tank, means interposed between the body of the floating roof and said shell and supported against said body by the buoyant effort of the oil, and spring devices for yieldingly holding said means against the shell. 100

2. In an oil tank, a floating roof comprising a body of smaller dimension than the shell of the tank, and means supported by the buoyant effort of the oil and adapted to support said body and to reciprocate radially for sealing the space between said body and the shell. 105

3. In an oil tank, a floating roof comprising a body of smaller dimension than the shell of the tank and means adapted to support said body and to float on the oil for sealing the space between said body and the tank. 115

4. In an oil tank, a floating roof comprising a body of smaller dimension than the shell of the tank and means for sealing the space between said body and the shell including a plurality of floating blocks adapted to be held in supporting contact with said body by the buoyant effort of the oil. 125

5. In an oil tank, a floating roof comprising a body of smaller dimension than the 130

- shell of the tank, floating blocks for sealing the space between said body and shell, and means for yieldingly holding said blocks in contact with the shell, said blocks having 5 radial sliding contact with said body.
6. In an oil tank, a floating roof comprising, in combination, a body of smaller dimension than the shell of the tank, radially movable sector shaped floating blocks for 10 closing the space between said body and shell, and means for sealing the openings between adjacent blocks.
7. In an oil tank, a floating roof comprising, in combination, a body of smaller dimension than the shell of the tank, floating 15 blocks for closing the space between said body and shell, and plates secured to said blocks adapted to overlap for sealing the openings between adjacent blocks.
- 20 8. In an oil tank, a floating roof comprising, in combination, a body of smaller dimension than the shell of the tank, floating blocks for closing the space between said body and shell, plates secured to the top of said blocks and adapted to overlap for sealing 25 the openings between adjacent blocks, said plates having extensions engaging the shell of the tank, and spring means for yieldingly maintaining said extensions in 30 contact with the shell.
9. In an oil tank, a floating roof comprising, in combination, a body of smaller dimension than the shell of the tank, floating blocks for closing the space between said 35 body and shell, plates secured to the tops of said blocks and adapted to overlap for sealing the openings between adjacent blocks, said plates having extensions formed with vertical faces and cam shaped upper ends, 40 and spring means for yieldingly maintaining said vertical faces in contact with the shell whereby said blocks may be moved gradually inward against the tension of said spring means when said cam ends and vertical faces encounter rivet heads or other 45 obstruction on the shell.
10. In an oil tank, a floating roof comprising, in combination, a body of smaller dimension than the shell of the tank, floating 50 blocks for closing the space between said body and shell, plates secured to the tops of said blocks adapted to overlap and strips secured to the bottom of said blocks adapted to extend slightly under the adjacent block 55 for sealing the openings between the blocks.
11. In an oil tank, a floating roof comprising, in combination, a body of smaller dimension than the shell of the tank, floating blocks provided with cam shaped outer 60 ends for closing the space between said body and shell, plates secured to said blocks having substantially vertical surfaces for engaging the shell and inturned upper ends, and spring means tending to maintain the 65 vertical surfaces in contact with the shell whereby said blocks may be moved gradually inward against the tension of said springs when said cam or inturned ends encounter a rivet head or other obstruction in the shell of the tank. 70
12. The combination with the shell of an oil tank, of a floating roof comprising a body of smaller dimension than said shell, means adapted to float on the oil for sealing the space between said body and tank, spring 75 devices for yieldingly holding said means against the shell, and coacting cams for positively moving said means inwardly against the tension of said devices when the float is near the top of the tank. 80
13. The combination with the shell of an oil tank, of a floating roof comprising a body of smaller dimension than the shell of the tank, means supported by the buoyant effort of the oil and adapted to reciprocate 85 radially for sealing the space between said body and the shell, and a cam fixed to the shell near the top thereof adapted to contact with said means as the floating roof approaches the top of the tank for moving said means inward and permitting the oil to flow over the top of the tank through the space thus formed between said means and the shell. 90
14. The combination with the shell of an oil tank, of a floating roof comprising, a body of smaller dimension than said shell, floating blocks for closing the space between said body and shell, plates secured to the tops of said blocks and adapted to overlap for sealing the openings between adjacent blocks, said plates having extensions formed with upper cam shaped ends, spring means for yieldingly maintaining said extensions in contact with the shell, and means adapted to engage said cam shaped ends for moving said blocks inwardly against the tension of said spring means when the oil level approaches the top of the shell. 95
15. In an oil tank, a floating roof comprising a body of smaller dimension than the shell of the tank, a plurality of blocks maintained against said body by the buoyant effort of the oil, and springs for holding said blocks in contact with the shell for sealing the space between said body and shell and permitting independent radial movements of said blocks. 100
16. The combination with the shell of an oil tank, of a floating roof comprising a body of smaller dimension than said shell, means for normally closing the space between said body and tank, and cam devices for positively moving said means for opening said space when the float approaches the 105 top of the tank. 115
17. A roof for tanks comprising a body of smaller diameter than the interior of the tank, radially movable sector shaped blocks adapted to float on the liquid in said tank 120
18. A roof for tanks comprising a body of smaller diameter than the interior of the tank, radially movable sector shaped blocks adapted to float on the liquid in said tank 125
19. A roof for tanks comprising a body of smaller diameter than the interior of the tank, radially movable sector shaped blocks adapted to float on the liquid in said tank 130

and to support said body, said sector shaped blocks being adapted to move radially under pressure, and means movable radially with the blocks for covering the space between 5 said sector shaped blocks.

18. A tank for containing liquid, a roof comprising a body of smaller diameter than the internal diameter of the tank, sector shaped blocks adapted to float on the liquid 10 supporting said body, movable radially rel-

ative thereto, said blocks being limited to radial and vertical movement.

In testimony whereof I have hereunto set my hand in presence of two subscribing witnesses.
